E. E. EDDY,
RAIL TIE AND FASTENER.
APPLICATION FILED JAN. 23, 1917.

1,242,334.

Patented Oct. 9, 1917.

By *O. H. Campbell, Jr.*
Attorney

UNITED STATES PATENT OFFICE

EARL E. EDDY, OF STONY CREEK, NEW YORK, ASSIGNOR OF ONE-HALF TO ARTHUR L. EDDY, OF STONY CREEK, NEW YORK.

RAIL TIE AND FASTENER.

1,242,334.

Specification of Letters Patent.

Patented Oct. 9, 1917.

Application filed January 23, 1917. Serial No. 143,915.

To all whom it may concern:

Be it known that I, EARL E. EDDY, a citizen of the United States, residing at Stony Creek, in the county of Warren and 5 State of New York, have invented certain new and useful Improvements in Rail Ties and Fasteners; and I do hereby declare the following to be a full, clear, and exact description of the invention, such as will enable others skilled in the art to which it 10 pertains to make and use the same.

This invention relates to improvements in metallic rail ties of that type, having their upper or top walls provided with rail seats, 15 and having cushion elements for the rails located within the seats; and the primary object of the invention is to admit of cushion elements of various widths being employed and effectively held within the seats.

20 Another object of the invention is to associate with each tie a novel form of rail fastening device that will effectively hold the rail against creeping or spreading, and so mounted on the tie that accidental disconnection of the fastening device will be prevented.

25 A further object of the invention is the provision of a metallic tie, formed of opposed and detachably connected sections, 30 which are effectively insulated from each other, so that the tie can be readily employed on a railroad equipped with block, or other suitable signaling system, and can also be employed on an electric railway.

35 Other objects will appear and be better understood from that embodiment of my invention of which the following is a specification, reference being had to the accompanying drawing forming a part thereof, in 40 which:

Figure 1 is a side elevation of a tie constructed in accordance with my invention, showing the tie equipped, at each end, with an improved type of rail-fastening device.

45 Fig. 2 is a detail plan view of one end of the tie with the adjacent rail partly in section, and also showing the connection between the opposed sections of each tie, partly in section,

50 Fig. 3 is a detail perspective view of one of the sections of which the tie is composed with the cushion and rail-fastening device removed therefrom,

Fig. 4 is a front elevation of the insulating

element that insulates the opposing sections 55 of the tie from each other,

Fig. 5 is a perspective view of a filler designed to be positioned in one of the rail seats, so as to admit of a cushion element, having a width less than the width of the 60 rail seat, being employed, and

Fig. 6 is a side elevation of one of the rail-fastening elements removed from operative position.

Referring to the drawing in detail, and 65 particularly to Fig. 1 of the drawing, the tie is shown as consisting of a pair of metallic and hollow sections 1. The sections 1 of the tie are arranged in opposing relation, and the opposing ends of the respective sections are provided with rectangular shaped flanges 2, which are secured to each other by means of bolts 3, which extend through apertures formed in the respective flanges 2. Interposed between the flanges 2, of the sections 1, is a rectangular-shaped element 4, formed of any suitable insulating material, and has openings therein for the passage of 70 the fastening bolts 3. The fastening bolts 3 have jackets or sleeves 5 surrounding the 75 same, as shown in Fig. 2 of the drawings, the said jackets or sleeves 5 being formed of suitable insulating material, and each bolt is also provided with a pair of washers 6, 80 which are also formed of insulating material and are located adjacent the opposite ends of the bolts and engage the outer faces 85 of the respective flanges 2. Each section 1 of the tie has its upper or top wall provided, adjacent the outer end thereof, with a cut-out portion 7, which forms a rail seat, and 90 which receives a cushion element 8, formed preferably of rubber, but it is to be understood that wood or any other material can 95 be employed. The cushion element 8 engages beneath the base flange of a rail 9, so as to admit of the desired cushioning effect being had for the rail during the passage of rolling stock over the rails of the track. The cushion elements 8 are to be of 100 the same widths as the base flanges of the rails employed; that is if rails having base flanges of approximately the same width as the seats 7 are used, then cushion elements 105 of widths approximately equal to the width of the seats 7 will be employed, and if rails are used that have base flanges of a smaller width than the seats 7, then cushion ele-

ments of the size of the smaller base flanges will be employed. With cushion elements of the latter type, that is those that have widths less than the widths of the seats 7, as shown 5 in Figs. 1 and 2 of the drawing, fillers 10 are employed. Each filler consists of a rectangular shaped plate 10, which is adapted to be inserted within one of the recesses and to be interposed between one of the longitudinal 10 edges of the adjacent cushion element and one of the side walls of the seat 7, as shown in Fig. 2 of the drawing, so as to fill the space left between the cushion element and one of the walls of the seat 7, so as 15 to prevent lateral shifting of the cushion element. It will, of course, be understood that the widths of the fillers to be employed will depend upon the widths of the spaces between the cushion elements employed and 20 the adjacent walls of the seat 7.

Each side of each section 1 of the tie is provided, adjacent the outer end of the tie, with a recess 11, which opens into the upper wall of the tie body, as shown more 25 particularly in Fig. 3 of the drawing. The recesses 11 extend beneath the seat 7 and elongated plates 12 are fitted within the recesses 11 and have their upper edges provided with cutout portions 13, the walls of 30 which lie flush with the walls of the adjacent seat 7. The plates 12 are also provided with vertically disposed recesses 14, one of the recesses 14 being located to one side of the cutout portion 13 and has its 35 upper end opening through the upper edge of the plate 12, and the other recess 14 has its upper end opening through the lower wall of the cutout portion 13, as shown in Fig. 3 of the drawing. The inner walls of 40 the recesses 14 are provided with openings 15 for the reception of bolts 16, which extend transversely through the tie body, so as to hold the plates 12 in operative position. Associated with each side of each 45 section 1, adjacent the outer end thereof, are a pair of rail fastening elements each of which is designated, as an entirety, by the numeral 17. Each rail fastening element 17 comprises a vertical portion 18, 50 which is adapted to be removably received by one of the recesses 14 in the adjacent side of the tie body, and a laterally extending portion or head 19 that is formed integral with the upper end of the stem 18, the said 55 head 19 being adapted to engage over the adjacent longitudinal side of the base flange of the adjacent rail 9, as shown more particularly in Fig. 1 of the drawing. Each head 9 has its inner side provided with a 60 laterally extending shoulder 20 which over-

lies the top wall of the tie body. The laterally extending shoulders on those fastening devices 17, which are received by those recesses 14 which have their upper ends opening into the cutout portions 13, overlie the filler plates 10, so as to prevent vertical movement of the filler plates when the latter are in operative position. It will, of course, be understood that the width of the space between each pair of recesses 14 will 65 depend upon the width of the base flange of the rails employed, so as to admit of the fastening element 17 being accurately positioned to engage the base flanges of the rail; and also upon the widths of the filler 70 plates 10, employed, so that the latter can be engaged by the shoulders on those fastening elements 17 that are received by the recesses 14 which communicate with the cutout portions 13.

Various changes might be resorted to in the construction, form and arrangement of the several parts without departing from the spirit and scope of the invention as 80 claimed.

Having thus described my invention what I claim as new, is:

1. A rail tie comprising a body portion having cutout portions in the upper wall thereof to provide rail seats, cushion elements located within the seats, a filler positioned within each cutout portion and interposed between one of the walls of the cutout portion and the adjacent cushion element, rail-fastening elements associated with the tie and arranged, respectively, on opposite sides of the tie, and laterally extending shoulders carried by certain of the rail-fastening elements and overlying the fillers, for the purpose specified.

2. A rail tie comprising a body portion having rail seats formed on the upper wall adjacent the opposite ends thereof, plates located on opposite sides of the body and disposed below the rail seats and having recesses therein, rail fastening elements associated with the plates and each including a vertical portion received by one of the recesses in the adjacent plate, a rail base flange-engaging portion carried by the upper end of the vertical portion, and a lateral extension carried by the rail flange-engaging portion and overlying the upper wall of the tie body.

In testimony whereof I affix my signature 115 in presence of two witnesses.

EARL E. EDDY.
